United States Patent Office

Des. 197,965
Patented Apr. 14, 1964

197,965

PASSENGER CARRIER

Dominic A. Saporito and Samuel M. Highberger, Birmingham, Mich., assignors to Clark Equipment Company, a corporation of Michigan

Filed Nov. 4, 1963, Ser. No. 77,269

Term of patent 14 years

(Cl. D14—3)

FIG. 1

FIG. 2

FIG. 3

FIG. 4

FIG. 5

FIGURE 1 is a side view of a passenger carrier, showing my new design;

FIGURE 2 is a front perspective view thereof;

FIGURE 3 is a rear perspective view thereof;

FIGURE 4 is a perspective view taken from the rear and above the passenger carrier; and

FIGURE 5 is a front end view thereof.

The dominant features of our design reside in the portions illustrated in solid lines.

We claim:

The ornamental design for a passenger carrier, as shown and described.
